Fig. 1 is a top plan view of my extruded doughnut;
Fig. 2 is a bottom plan view of the same;
Fig. 3 is a perspective view of the same.

I claim:

The ornamental design for an extruded doughnut, as shown and described.

This application is a substitute for my inadvertently abandoned application Serial No. D. 24,519 filed on April 15, 1953, which was a continuation-in-part of my application Serial No. D. 22,717 filed on December 15, 1952, and now abandoned.
